Specification for Design.

Patented Nov. 30, 1915.

Application filed August 12, 1915. Serial No. 45,253. Term of patent 7 years.

To all whom it may concern:

Be it known that I, GEORGES REYBET, a citizen of the French Republic, residing at New York, N. Y., have invented a new, original, and ornamental Design for Carpets, of which the following is a clear, full, and exact description.

Referring to the accompanying drawing forming a part thereof, a portion of a carpet is shown which bears the design. In the illustration of my design shown in the drawing a represents black, b light green, c dark green, and d brown.

What I claim is:

The ornamental design for a carpet, substantially as shown.

GEORGES REYBET.
